WINDOW SHUTTER

Marcel Demeulenaere, Coq-sur-Mer, Belgium

Application May 29, 1930, Serial No. 457,416, and
in Belgium July 13, 1929

2 Claims. (Cl. 156—16)

My present invention relates to window shutters of the type in which the shutter is adapted to be wound around a roller actuated mechanically, and more particularly to devices for balancing shutters of this type.

Such window shutters may be balanced either by using an invariable balance weight and varying the length of the lever to which said balance weight is attached by the application of a pulley 10 of varying diameter or any other similar device, or by using a varying balance weight with a constant length of lever.

The object of my present invention is to provide an improved balancing device of the last 15 mentioned type.

Broadly stated the varying balance weight of my invention is constructed in such a way that it may be formed of parts which are always similar for any size, width, thickness, weight, etc. 20 of the window shutter, and adapted to be manufactured by punching or in any other similar way, in the shape of blades or the like. A number of such blades are assembled to form a section of the balance weight and these sections are 25 pivotally connected to each other in zig-zag form to constitute the entire balance weight.

In order that my invention may be easily understood, I have illustrated the same by way of example in the accompanying drawing, in 30 which:

Fig. 1 is a front elevation of the window shutter in its closed position.

Fig. 2 is a corresponding side elevation, and

Fig. 3 is a section on line 3—3 of Fig. 2.

Referring now more particularly to the drawing, V designates the shutter adapted to be wound around a roller A from the diameter DA to the diameter DA', DM being the average diameter thereof. Made integral with the roller A is a 40 smaller roller A' around which a belt or cable C may be wound up from the diameter da to the diameter da', dm being the average diameter. After the shutter V has been lowered, it will act on the diameter DA and the belt or cable C which 45 is now wound around the roller A' will act on the diameter da', that is the maximum diameter. Attached to said belt or cable C is a series of balance weights La, the total weight of which exactly balances the weight of the shutter. P 50 and p designating the total weight of the shutter and balance weight respectively. It will be obvious that $P \times DA = p \times da'$, the frictions on the guide rollers F and f for the shutter V and belt C respectively being not taken into consideration.

55 In the case in which the balance weight is at-

tached to a cable I may also maintain a constant winding diameter equal to dm . The shutter V of a weight P being wound upon a diameter D, I will have $P \times D = p \cdot dm$.

In accordance with the raising of the shutter V, 60 the balance weights or section La will be made inoperative, the lowermost sections La resting on the ground and the following sections being successively placed upon said lowermost section and upon each other.

After the shutter has been completely raised, all the sections of the balance weight will rest on each other. The blades La are pivotally connected together by means of pins a journaled in thin bushings d secured to plates fs. After all the 70 balance weight sections have been raised, they will have the appearance of an accordéon. The shutter will be opened according to the lowering of the balance weight sections. The number of sections may be varied as desired and the number 75 of blades in each section may be determined according to the graduation of the weight of the shutter.

This result may be obtained by using extended pins a and securing the thin blades La side by side. 80 In this way, I will obtain an increase of weight with the same parts constituting the balancing device for shutters of any size, width, thickness and weight.

I claim:

1. In a shutter of the kind described, the combination with a rotatable roller and a shutter adapted to be wound around said roller, of a reduced roller made integral with the first named roller, a belt adapted to be wound around said reduced roller, a balance weight attached to said belt, said balance weight being formed of a number of sections, alternately attached to each other at opposite ends by means of pivotal connections, whereby said sections will be adapted to rest on the ground and on each other according to the raising of the shutter, substantially as set forth.

2. In a shutter of the kind described, the combination with a rotatable roller and a shutter adapted to be wound around said roller, of a reduced roller made integral with the first named roller, a belt adapted to be wound around said reduced roller, a balance weight attached to said belt, said balance weight being formed of a number of sections and each section being formed of a number of similar blades, and means for connecting said blades together and pivotally connecting said sections alternately at opposite ends, substantially as and for the purpose set forth.

MARCEL DEMEULENAERE. 110
